CLAIM

The ornamental design for a container with lid as shown and described.

DESCRIPTION

FIG. 1 is a perspective view of a first component of a container with lid, shown separately for completeness of illustration;

FIG. 2 is a top plan view thereof;

FIG. 3 is a front elevation view thereof, the rear elevation view being identical;

FIG. 4 is a left side elevation view thereof, the right side elevation view being identical;

FIG. 5 is a bottom plan view thereof;

FIG. 6 is an exploded perspective view of the container with lid;

FIG. 7 is a perspective view of a second component of the container with lid, shown separately for completeness of illustration;

FIG. 8 is a top plan view thereof;

FIG. 9 is a left side elevation view thereof, the right side elevation view being identical;

FIG. 10 is a front elevation view thereof, the rear elevation view being identical; and,

FIG. 11 is a bottom plan view thereof.

The broken lines shown illustrate portions of the container with lid and form no part of the claimed design.

1 Claim, 9 Drawing Sheets
